UNITED STATES PATENT OFFICE.

HUGO PETZOLDT, OF DINUBA, CALIFORNIA.

POWER-LIFT IMPLEMENT.

Application filed March 6, 1923. Serial No. 623,148.

My invention relates to earth working tools and more particularly to a power lift for heavy earth working tools, such as sub-soil plows, cultivators, road levelers, and road building machinery. The object I have accomplished is the raising of earth working tools relative to the carriage at the will of the operator, and with a light operation of a lever. This and other objects hereinafter set forth are accomplished by means of the device hereinafter described and illustrated on the accompanying drawing in which Figure 1 is a side view of the vehicle, showing the mechanism of the lift. Figure 2 shows a pawl and ratchet which is a part of said device. Figure 3 shows the assembled trip and eccentric. Figure 4 is a view of the ratchet. Figure 5 is an end view of a lever and an eccentric.

In said drawings, 1 is the carriage beams carrying the implement. 2 is a subsoil plow, and 4 an axle constructed with two horizontally aligned spindles 6, with an axis 8 which is parallel with spindles 6, and a spaced distance therefrom, and with connecting arms 4. Wheel 5 is adapted to rotate on spindle 6, and the axis 8 is rotatable in a bearing 9 which is attached to the beam 1. To wheel 5 I have attached a ratchet 10 which is concentric with said wheel. The ratchet consists of two rings or discs 11 and 12 which are connected with a plurality of stops constructed of rollers 23 held in position with studs 24. These stops are spaced apart, and are adjacent to the periphery of the discs.

On the under side at the rear end of beam 1, I have pivoted a pawl 15 which is adapted to engage with either of the stops or rollers 23, thus forming a connection between the beam 1 and the hub of the wheel which results, in combination with the rotation of the wheel, in raising the beam 1 and any implement which may be attached thereto. Lever 25, shown in the drawing, is formed integral with, or attached to pawl 15, for the purpose of moving the pawl in operative relation with the ratchet. It is noted that the hook 15^a on pawl 15 is adapted to hold the ratchet until the wheel has rotated so that the next roller to the one engaged moves under the pawl 15 and kicks it out of operative relation. The spring 27 assists in normally holding the pawl 15 out of operative relation with ratchet 10.

The lever 16 is formed integral, or rigidly attached to the axis 8, to which lever a sliding bar 17 is pivoted. Sliding bar 17 has a notch 18 which co-operates with a stop pin 19, attached to a post 29. The mechanism heretofore described is timed so that when the pawl 15 is kicked out of operative relation with the ratchet the notch 18 is engaged with the pin 19 and the implement is thus held in a raised position. To post 29 is pivoted a lever 31 to which is attached an eccentric adapted to rotate under sliding lever 17, so that by operating said lever and eccentric the sliding bar can be released from stop 19. Such release results in the sliding bar moving backward with the forward movement of the carriage, thus permitting the plow or implement to be drawn into or towards the earth. The depth the plow or implement can enter the earth is regulated by a series of holes in the end of sliding bar 17 into one of which a stop bolt 21 is inserted adapted to strike post 29, which prevents the sliding bar from moving beyond a defined point.

The spring 33 is adapted to normally hold the lever 31 in position so that notch 18 can be in operative relation with pin 19.

The ropes 40 and 41 shown are merely for conveniences of operating the levers to which they are attached.

The operation of the device is as follows: When it is desired to raise the implement, pawl 15 is placed in operative relation with ratchet 10, and the forward movement of wheel 5 raises the beam and implement attached thereto which is then held in the raised position by sliding rod 17 and pin 19. When it is desired to lower the implement the sliding bar 17 is released from pin 19 by means of lever 31 and eccentric 32, and as the pawl 15 has automatically been released, the implement can assume its normal position which would be to drop to the earth.

Attention is called to the fact that in my device the wheel 5 is not locked so that it will drag, but the movement of said wheel raises the beam and implement, and when raised the pawl is automatically disconnected.

Having described my invention, I claim:

1. In a power lift implement, a frame, an axle journaled transversely of said frame, an arm on each end of the axle, each arm terminating at the lower end with a spindle,

- traction wheels rotatable on said spindle, a pair of spaced disks mounted on one spindle and fixed to the adjacent wheel, a plurality of pins extending transversely between the 5 disks, and at regular intervals in a circular formation adjacent the edges of the discs, an elongated pawl pivotally mounted on the frame at a point underneath the axis of the axle and normally extending forwardly 10 alongside of the adjacent arm, said pawl having a hooked end terminating above the pins, means for swinging the pawl into an engageable position with said pins, whereby when the hooked end is engaged with one 15 pin and the disks rotate, the next succeeding pin will engage the pawl to disengage the hooked end.
2. In a power lift implement, a frame, an axle journaled transversely on said frame, 20 an arm on each end of the axle, each arm terminating at its lower end with a spindle, traction wheels rotatable on said spindles, a pair of spaced disks mounted on one spindle and fixed to the adjacent wheel, a plurality of pins extending transversely between the 25 disks, and at regular intervals in a circular formation adjacent the edges of the disks, an elongated pawl pivotally mounted on the frame underneath the axis of the axle and having a hooked end terminating above the 30 pins, said pawl normally extending forwardly alongside of the adjacent arms, means for swinging the pawl into an engageable position with the pins whereby when the hooked end is engaged with one pin and the disks 35 rotate, the next succeeding pin will engage the pawl to disengage the hooked end, a crank projecting from the axle, a bar pivotally engaged with the crank and having a notch, a pin, and a supporting structure on 40 the frame for the last mentioned pin so that said last mentioned pin may be engaged by the notch of the bar.

HUGO PETZOLDT.
